G. O. WILSON,
FENCE STRETCHER CLAMP,
APPLICATION FILED JUNE 9, 1917.

Patented Jan. 22, 1918.

UNITED STATES PATENT OFFICE.

GEORGE O. WILSON, OF WHEATLEY, KENTUCKY.

FENCE-STRETCHER CLAMP.

1,254,458.

Specification of Letters Patent. Patented Jan. 22, 1918.

Application filed June 9, 1917. Serial No. 173,825.

To all whom it may concern:

Be it known that I, GEORGE OLIVER WILSON, a citizen of the United States, residing at Wheatley, in the county of Gallatin and State of Kentucky, have invented certain new and useful Improvements in Fence-Stretcher Clamps; and I do hereby declare the following to be a full, clear, and exact description of the invention, such as will enable others skilled in the art to which it appertains to make and use the same.

This invention relates to improvements in fence stretcher clamps.

The object of my invention is to provide a fence stretcher clamp which will firmly hold a fence wire and be so locked that the wire will be held against accidental movement.

A further object of the invention is to provide a clamp of this character, which will be so constructed as to effectually clamp a series of wires and hold the same against movement while a pulling action is applied thereto for stretching the same.

A still further object of this invention is to provide a device which will remain in its locked position regardless of the amount of pull exerted on the clamp.

A still further object of this invention is to provide a pair of clamping boards upon which is removably arranged a locking element which, when in locked position, will securely hold the boards together binding them against fence wire which is arranged between their opposing faces, and the boards will be held against movement due to the locking action of the locking member.

A still further object of this invention is to provide a device of this character, which will be simple, practical and comparatively inexpensive in construction, and one that can be manufactured and sold at a low cost.

With these and other objects in view the invention consists in the novel combination and arrangement of parts which will be hereinafter more fully set forth and pointed out in the claims hereto appended.

In the drawings:

Figure 1 is a perspective view illustrating the clamp, showing it in its unlocked position and showing the position of the lever as it would appear in its unlocked position and the manner in which the lever appears when in its locked position is shown in dotted lines.

Fig. 2 is a transverse sectional view taken on the line 2—2 of Fig. 1.

Like numerals of reference designate corresponding parts in all the figures of the drawings.

Referring to the drawings, numerals 1 and 2 designate the upper and lower clamping elements, which are formed of steel or any other suitable material, and the lower clamping element is provided on one face with a longitudinally extending groove 3 in which is adapted to be removably arranged a bead or longitudinally extending rib 4 carried by the opposing face of the upper clamping element 2, and it will thus be seen that a device is provided that will firmly engage a fence wire and lock the same against movement when placed between the opposing faces of the clamping elements.

Secured to the lower strip or element 2 near each end is a U-shaped bar 5 which is formed of a single strip of material, and the arms of which are arranged to support laterally extending cylindrical extensions 6, as clearly shown in Fig. 1. Similar U-shaped bars 7 are secured near the ends of the upper clamping element 1, the arms of which are provided at their free ends with lateral extensions 8 having formed therein apertures 9. Secured centrally of the upper face of the upper clamping element 1 a suitable bearing or wear plate 10, on which the eccentric of a locking member, which will be hereinafter more fully described, bears.

The locking mechanism, is designated in its entirety by the numeral 11, and it comprises a cam 12 which is arranged to bear against the plate 10, as illustrated in the drawings. This cam is provided with an integral lever 13 which forms a means by which the cam may be rotated by the hand of the operator. Formed near the upper edge of the cam is a bore 14, the use of which will appear as the description proceeds.

This cam is also provided near its center with another bore 14' and adjacent its lower edge with a bore 14'', the use of which will appear as the description proceeds.

Suitable substantially U-shaped wires 15 are provided. These wires have their web portions extended through the bore 14 and 14'' and their arm portions extend parallel with the side edges of the clamping element 110

1 and extend through the apertures 9 in the extensions 8 of the U-shaped members 7. The ends of the wires terminate into loops 16 which are arranged to surround the cylindrical extensions 6, and thus form a pivotal connection with the lower clamping element 2. The apertures 9 are of such a shape as to permit of the removal of the wires 15.

10 A wire 17 is substantially U-shaped and is of a length shorter than the first named U-shaped members and has its web portion arranged through the bore 14' in the cam. The ends of its arms are looped and are adapted to engage extensions 18 carried by a U-shaped member 19 which is supported centrally on the lower clamping element 2, and thus arranged to exert the necessary pressure centrally of the clamping element, 15 as clearly illustrated in the drawings.

20 It will be apparent from the foregoing that in use the wire to be clamped or stretched is passed between the opposing faces of the clamping elements 1 and 2 and by forcing or applying pressure upon the lever 13 and forcing the same downwardly into the position illustrated in full lines in Fig. 1, it will move the cam member in such a position as to prevent the members from 25 being drawn away from each other, thereby locking them in this position and against the wire between their opposing faces which will allow a stretching device to be secured thereto to secure the proper stretching of 30 the fence wire.

35 It will be noted that by virtue of the U-shaped members being pivotally secured to the cam head and when the lever end of the cam is parallel with the clamping elements 40 that the pull will be directed on the head in such a manner to hold the lever in this position thus holding the elements 1 and 2 in clamping engagement with one and another and against the fencing wire which 45 is located between the opposing faces.

What is claimed is:

1. A fence wire stretcher including a pair of clamping elements, links adjacent the ends of each of the elements, U-shaped wires 50 extending through the links, an operating lever, a cam carried by the lever bearing against the upper element, and a lever to control the rotation of this cam and thereby draw the wires upwardly to clamp the elements together, as and for the purpose specified.

55 2. A fence wire stretcher including a pair

of clamping elements, U-shaped bars secured to each of the clamping elements, one of the U-shaped bars being provided with apertures 60 at each end, annular extensions on the opposite U-shaped bar, wires extending through the apertures and connected to the annular extension on the last mentioned U-shaped bar, and a cam, the said wires being connected to the cam, and a lever to control the rotation of the cam and thereby draw the wires upwardly and clamp the elements together, as and for the purpose specified.

3. A fence wire clamp including a pair 70 of clamping elements, one of said elements provided with a longitudinal groove on one face thereof, a longitudinally extending arm formed on the opposing face of the other clamping element and arranged to register 75 with the groove to more firmly engage the wire which is to be stretched, a pair of U-shaped plates secured adjacent the end of each of the clamping members, bored extensions formed on the free ends of the arms 80 of the plates of the upper clamping element, lateral extensions on the arms of the U-shaped plates of the lower clamping element, a bearing plate secured centrally to the upper clamping element, a cam rotatable 85 on the bearing plate, said cam being provided with a plurality of bores, U-shaped wires extending through the apertures of the extensions of the plates of the upper clamping element and having looped ends 90 arranged around the extensions on the arms of the U-shaped plates of the lower clamping element, said wires arranged through the bore in the cam whereby when the cam is moved downwardly the clamping elements 95 will be drawn into engagement with one another to efficiently bind a wire between their opposing faces.

4. A fence wire stretcher including a pair 100 of clamping elements, bars secured to the clamping elements, a lever, said lever having a cam at one end thereof, a wear plate secured to the upper clamping element and adapted to receive the flat surface of the cam 105 of the lever when the lever is in position with the element locking the elements into engagement with one another as and for the purpose specified.

In testimony whereof I affix my signature in presence of two witnesses.

GEORGE O. WILSON.
